UNITED STATES PATENT OFFICE

WINFRED P. SHEPHERD, OF PASADENA, CALIFORNIA

DOOR HOLDER

Application filed April 24, 1928. Serial No. 272,475.

My invention relates to a simple, inexpensive and portable door holder which can be readily placed under the bottom of a door, on the floor, to hold said door in any desired position of ajar.

Among the salient objects of my invention are: to provide such a device having a base or body with a yielding member projecting therefrom and adapted to be depressed and inserted under the bottom of the door, that is, between the floor and the bottom of said door, and allow to press upwardly against the bottom edge of the door, said projection or extension pressing upwardly against the bottom of the door, while its base or body rests upon the floor; to provide such a device with a portion projecting from the outside away from the door and convenient to be depressed by the foot of a person, said device being adapted to be slipped under the bottom of a door by pushing it with the foot while the projecting part or extension is depressed, whereby when the foot is removed, said extension bears upwardly against the bottom of the door; to provide in a device of the character referred to an upstanding handle for the convenience of the user, whereby the projecting part or extension can be depressed by means of the handle, or by both the handle and the foot piece; and, in general, to provide a simple, practical and ornamental door holding device of the character referred to.

In order to fully explain my invention, I have shown one practical embodiment thereof on the accompanying sheet of drawings, which I will now describe;

In the drawings Figure 1 is a perspective view of the lower portion of a door, ajar, with my improved device in place thereunder, with the handle ornament standing against the side of the door;

Figure 2 is a plan view, partly in section;

Figure 3 is a side or edge view, partly in section, and

Figure 4 is an enlarged detail view of the dished disc for holding the upper end of a spring.

Referring now in detail to the drawings, my device as here illustrated, comprises a

body or base 4, provided on the underside with non-slip elements 5, and cut away in its middle portion in arch-form whereby to provide an opening or recess 6, opening downwardly. Movably mounted in this opening or recess 6, is an operating member 7, projecting to one side, as at 7' and in position to receive the foot of a person for depressing it. The opposite side of said member is provided with a holding member or extension 8, adapted to catch up against the bottom of a door after being inserted thereunder and released. Two coiled springs 9, 9, are seated up in the body or base 4, and attached at their lower ends to said operating member 7, and normally hold the said operating member in its up position. Said springs at their upper ends are attached to a dished disc 10, forced up into bores 11, in said base 4, said dished disc having a struck-down loop 10' to which the end of the spring is attached. At its lower end said springs are held by pins 12. The springs are extended when said operating member is depressed and operate to move said operating member upwardly against the bottom of the door when it is released.

A handle 13 is shown extended down through said body or base 4, and attached at its lower end to said operating member, between the springs, and at its upper end, said handle is provided with an ornament, here shown in the representation of a parrot 14.

Thus the device can be placed by using the handle and depressing the operating member thereby, or said operating member can be depressed by the foot, on the projecting part 7', and slipped under the door, or the door moved to and over the holding member or extension 8. It will be seen that the device will hold the door ajar in any position and constitutes an ornamental device conveniently used, or it can be embodied in a floor piece without the handle and operated by the foot, in the manner hereinbefore described. It is small, portable and practicable and will not scar or mark the side of the door.

I do not limit the invention to the details of construction shown for illustrative purposes, realizing that many changes can be

made therein without departing from the spirit thereof.

I claim:

1. A door holding device including in combination a base having a recess therein, a movable operating member in said recess and projecting to one side of said base to receive the foot of a person for depressing said operating member, an extension at the opposite side of said base on said operating member adapted to be slipped under the bottom edge of a door to engage and hold the same when released, and spring means normally moving said operating member upwardly against said door.
2. A door holding device including in combination a base, a movable member on said base, said movable member extending to one side of said base in position to be engaged by the foot of a person to depress the same, an extension from the opposite side of said movable member adapted to be slipped under the bottom edge of a door to engage and hold the same, spring means normally raising said movable member, and a handle attached to said movable member and extending upwardly along side of the door for operating said device by hand.

Signed at Los Angeles, Los Angeles County, California, this 1st day of March, 1928.

WINFRED P. SHEPHERD.
